UNITED STATES PATENT OFFICE.

FRANK D. SPOTSWOOD, OF LEXINGTON, KENTUCKY.

MOUTH-MASK.

1,265,129.

Specification of Letters Patent.

Patented May 7, 1918.

Application filed August 23, 1917. Serial No. 187,628.

To all whom it may concern:

Be it known that I, FRANK D. Spotswood, a citizen of the United States, residing at Lexington, in the county of Fayette and State of Kentucky, have invented certain new and useful Improvements in Mouth-Masks, of which the following is a specification.

This invention relates to an improved mouth mask, especially designed for use by children and has as its primary object to provide a device of this character which will be provided with the representation of the human mouth or other mask feature and which may be fitted, by a child, over the mouth to be held in position by the teeth for masking the mouth of the child.

And the invention has as a further object to provide a mask of the above nature which will be equipped with a supporting tab or flap which may be lightly held between the teeth to support the mask in position over the mouth of the child so that it will be unnecessary for the child to employ the hands for supporting the mask while, at the same time, the child may talk or distort its face while the mask is in place.

Other and incidental objects will appear as the description proceeds and in the drawings wherein I have illustrated the preferred embodiment of the invention and wherein similar reference characters designate corresponding parts throughout the several views:

35 - Figure 1 is a front elevation showing the manner in which my improved mask is applied to the face over the mouth,

Fig. 2 is a side elevation illustrating the manner in which the supporting tab of the mask is held between the teeth to retain the mask in position, and

Fig. 3 is a rear perspective view of the device particularly showing the mounting of a supporting tab for the mask.

45 In carrying out the invention, my improved mask is formed with a preferably elliptical body 10. However, the body may be of any other approved shape and is constructed of cardboard or any other suitable material. Upon its front side the body 10 is, as particularly shown in Fig. 1 of the drawings, provided with the representation

of a human mouth or other mask feature. In this connection it will, of course, be obvious that the body 10 could be provided with the representation of the mouth of an animal or other animal feature. Formed in the upper edge of the body, midway the representation of the mouth thereon, is a curved notch 11. Below this notch, the rear side of the body is equipped with a supporting tab 12. This supporting tab may also be formed of cardboard or any other approved material and, at one extremity, is pasted or otherwise secured to the body. The opposite extremity of the tab is, as particularly shown in Fig. 3, scored transversely so that the free end of the tab may be readily bent to extend rearwardly from the body.

In use, the body 10 of the mask is placed over the mouth of the child employing the device with the child's nose received within the notch 11 of the body. At the same time, the free extremity of the tab 12 is bent to project rearwardly from the body and is inserted between the teeth. The tab may thus be lightly held between the teeth to support the mask in position over the mouth. Consequently, it will be unnecessary to employ the hands for maintaining the mask in place while, at the same time, the child may talk or distort the face at pleasure.

It will therefore be seen that I provide an exceedingly simple device and one which will prove especially attractive to children. However, I do not wish to be limited in this regard since it will be obvious that the device is also adapted for use by older people.

Having thus described the invention, what is claimed as new is:

1. A mask including a body provided with a mask feature and adapted to be fitted by the user over a feature of the face for masking such feature of the face, and means carried by the body to normally lie thereagainst and movable to project laterally from the body to be received between the teeth of the user to support the body of the mask in position.

2. A mask including a body provided with a mask feature and adapted to be fitted by the user over a feature of the face for masking such feature of the face, and a flexible tab carried by the body and adapted to be

swung laterally therefrom to be received between the teeth of the user to support the body of the mask in position.

3. A mask including a body having a notch formed in one edge thereof and provided with a mask feature, the body of the mask being adapted to be fitted, by the user, over the mouth with the nose received with-

in said notch, and a tab secured at one extremity to the body below said notch and 10 adapted to be inserted at its opposite extremity between the teeth of the user to support the body of the mask in position.

In testimony whereof I affix my signature.

FRANK D. SPOTSWOOD. [L.S.]
